UNITED STATES PATENT OFFICE.

PETER R. RICHARDS AND LEON BLOCH, OF CLEVELAND, OHIO, ASSIGNORS TO THE REPUBLIC BRASS COMPANY, OF CLEVELAND, OHIO, A CORPORATION OF OHIO.

COMBINATION FAUCET FOR LAUNDRY TUBS AND SINKS.

Application filed February 14, 1924. Serial No. 692,648.

This invention relates generally to faucets for laundry tubs, and more particularly to one which is capable of delivering hot or cold water to either one of the compartments of a divided laundry tub.

The invention is also particularly adapted for use in connection with a sink or tub provided with a removable top, which, when the sink or tub is not in use, is arranged to pro-

vide a table.

The object of the invention is to provide an exceedingly simple construction of faucet, and supporting means therefor; the faucet and support being so arranged that the nozzle or spout can be shifted as desired without contacting with the support, another object is to provide a supporting means which can be used when the faucet is used in connection with a sink or tub provided with one of the removable table covers before referred to.

With these various objects in view, the invention consists in the novel features of construction and in the manner of arranging and combining the same, all of which will be fully described hereinafter and pointed out in the claim.

In the drawings forming part of this specification, Fig. 1 is a face view of a faucet constructed in accordance with the invention, and showing the practical application thereof; Fig. 2 is a vertical sectional view partly in elevation; Fig. 3 is a sectional plan view and Fig. 4 is a view showing a slightly modified form of support.

In carrying out the invention, there is provided a faucet body A to which are connected the hot and cold pipes B and C controlled by means of the valves D and E arranged at each end of the faucet.

The body A is formed with a centrally arranged forwardly and downwardly extending discharge member F to which is swiveled the nozzle or spout G. This swivel action is accomplished by providing the internally threaded gasket G' with a screw-thread for the externally threaded end of the discharge portion F, the inner end of the discharge spout or nozzle being slightly enlarged; and if desired a packing ring or washer may be interposed between this enlarged end and the gasket.

By this construction a non-leakable connection is provided but at the same time the nozzle or spout G can be swung to either side

as desired for the purpose of discharging the water into one or the other of the compartments of the tub.

The faucet body is formed with a depending lug H, the end of which is slightly tapered to fit into a correspondingly tapered socket I, arranged centrally of the curved or arched support K, the ends of said arched support being provided with feet K' which straddle and rest upon the rear wall L of the laundry tub, and upon opposite sides of the subdividing partition L'. Screws K² are preferably inserted through the rear sides of the feet K' for the purpose of securely connecting the support to the laundry tub.

If desired, a set screw L' can be employed for fastening the depending portion of the faucet in the socket I.

By means of a faucet, constructed and supported as herein shown and described, one is able to arrange the same close against the wall and above the rear wall of the laundry tub and a maximum of movement of the spout or nozzle G in either direction is permissible inasmuch as the central discharge portion F projects forwardly, and the upper end of the spout or nozzle is swiveled to the forward and lower end of this discharge portion. As before stated, it is not only possible to swing the nozzle from one side or the other in order to discharge the water into the particular compartment desired, but the spout or nozzle can be shifted entirely back out of the way without encountering any portion of the support.

Some laundry tubs or sinks are provided with covers which are turned down to provide a table when the sink or laundry tub is not in use. When it is desired to use the improved faucet in connection with a sink or tub of this character the support K of the type shown in Figs. 1 and 2 is dispensed with and in place thereof there is provided a plate M having a centrally disposed forwardly projecting socket M' into which screws the shank M² of the bolt N, the head N² of said bolt being provided with a tapered bore into which fits the tapered end H' of the centrally disposed depending lug H previously mentioned; and if desired, a set screw I' can be provided for securely fastening the lug of the faucet to the supporting bolt. The plate is fastened to the wall above

the sink or tub and the bolt N can be adjusted to the exact position desired and then the lug of the faucet is inserted therein and connected thereto.

The freedom of movement of the spout or nozzle is exactly the same in this form of support as in the form illustrated in Figs. 1 and 2 and the extent of this movement is illustrated in Fig. 3.

The body of the faucet and the support are exceedingly simple and inexpensive to manufacture, and the assemblage or connection of the parts into a unitary structure is likewise simple and inexpensive.

It will therefore be seen that there is provided a combination faucet of the character specified, which will fully carry out all of the objects, and successfully perform the various functions heretofore described.

Having thus described our invention, what we claim is:—

As a new article of manufacture a faucet for tubs and sinks comprising a body portion having inlet openings and a centrally arranged discharge spout projecting forwardly and downwardly from the central forward portion of said body, said body portion having a downwardly extending member arranged in line with the body portion and to the rear of the forwardly and downwardly extending spout, the lower end of said depending member being tapered and a support into which said tapering end fits together with means for securing the same.

In testimony whereof, we hereunto affix our signatures.

LEON BLOCH.
PETER R. RICHARDS.
